UNITED STATES PATENT OFFICE.

FRED RICHARD WEATHERSBY, OF HOUSTON, TEXAS.

DRILL.

1,077,772.

Specification of Letters Patent.

Patented Nov. 4, 1913.

Application filed January 25, 1913. Serial No. 744,139.

To all whom it may concern:

Be it known that I, FRED R. WEATHERSBY, a citizen of the United States, and a resident of Houston, in the county of Harris and State of Texas, have invented an Improvement in Drills, of which the following is a specification.

My invention relates to drills for general use and more particularly to drills especially adapted for use in connection with rock and earth formations.

The more particular purpose of my invention is to provide a drill in which there are a number of separate cutters detachably secured upon a head, the various parts being so arranged and connected as to present a number of advantages.

Reference is made to the accompanying drawings forming a part of this specification and in which like letters indicate like parts.

Figure 1 is a substantially central vertical section through my improved drill and is taken upon the line 1—1 of Fig. 2, looking in the direction of the arrow. Fig. 2 is an inverted plan of my improved drill. Fig. 3 is a top plan view of the drill, some of the cutters and parts associated therewith being removed. Fig. 4 is a detail showing in plan the cutter disk forming a part of the drill. Fig. 5 is a perspective view showing one of the cutters removed. Fig. 6 is a detail showing another form of cutter which is provided with a single cutting tooth. Fig. 7 is a perspective showing another form of cutter which in this instance is provided with two cutting teeth. Fig. 8 is a perspective of the central cutting member which serves the double purpose of a centering bit and a cutter.

The shank 9 carries an annular flange 10 integral with it. A disk 11 having the same diameter as the annular flange 10 is provided with holes 12, 12^a, 13, of angular cross section for accommodating the stems of certain of the cutters, as hereinafter described.

Two cutting blades or teeth 15 are carried by a cutter 14, the latter being provided with a stem 16, the upper end of which is threaded and fitted with a nut 17. This nut is housed in a countersink 16^a, as will be understood from Fig. 1.

At 18 are shown four cutters, each having a length nearly equal to the radius of the

disk 11 and being provided with teeth 19. Each cutter 18 is provided with two stems 20, 21, these stems being square in cross section except at their upper ends 22, these ends being threaded and fitted with nuts 23. The cutters 18 are further provided with square stems 24, the upper ends 24^a of the latter being fitted with nuts 25. These nuts are housed in countersinks 24^b within the disk 11.

I provide a number of cutters 26 of the type shown more particularly in Fig. 7. Each cutter of this type has two teeth 27 and a square stem 28, the latter at its upper end being rounded and threaded at 29. I also provide other cutters 30 of the type shown in Fig. 6. The cutter 30 is provided with a single cutting tooth 31 of considerable width. It is further provided with a stem 32 which is square in cross section and carries a rounded threaded portion 33 at its upper end.

For accommodating the cutters 26, 30, I provide the disk 11 with square holes, 35, spaced systematically with reference to the other holes, as will be understood from Fig. 4.

In assembling the various parts, I first take up the cutters 18 and pass the stems 24 through the disk 11 and, by applying the nuts 25, secure the cutters 18 to the disk. I next extend the stem 16 of the cutter 14 through the middle hole 13 of the disk 11 and by applying the nut 17, I secure this cutter 14 firmly to the disk. I next place the disk 11 against the flange 10, turning the disk, if necessary, to some extent so as to bring the stems 20, 21, into registry with the holes in the disk 10. The stems 20, 21, being now threaded through the disk 10, the nuts 23 are applied, as indicated in Fig. 1.

It will be noted that the stems 20, 21, carried by the cutter 18 holds the disk 11 upon the flange 9, whereas the stems 24 merely hold the inner ends of the cutters 18 tightly against the adjacent portions of the disk 11, the stems 24 having no immediate connection with the shank 9 or the flange 10. Similarly the cutter 14 is not connected with the shank 9 or the disk 10.

Whenever the disk 11 is taken off none of the cutters 14, 18 become loose relatively to the disk. It is different, however, with the cutters 26, 30. The stems 28, 32, of these

cutters are analogous to the stems 20, 21, of the cutter 18 and are held in position by aid of nuts 23. When, therefore, the nuts just mentioned are taken off in order to dis- 5 engage the disk 11, the cutters 26, 30, are loosened relatively to the disk.

Extending entirely through the drill are holes 34, through which water flows in order to wash away the debris.

10 The cutter 14 carrying the two blades 15 serves not only the purpose of a cutter but also that of a centering bit around which the various other cutters revolve in circles while the drill is in action.

15 It will be noted that the stems 16, 24, which are comparatively short and are totally disconnected from the shank 9 and disk 10, are located comparatively near the center of the drill. On this account the lever- 20 age exerted on the stems in question and parts carried thereby is considerably less than that to which the longer stems are exposed. This fact gives my construction a peculiar advantage in that the stems 20, 21, which sustain relatively the greatest lever- 25 age, are secured firmly to the annular flange 10 and thus enabled to stand the excessive strain thrown upon them.

The various cutters are removable and re- 30 placeable independently of each other.

The operation of my device is as follows: The parts being arranged and assembled as above described, the shank 9 is connected with the operating mechanism of the drill

and being forced against the earth is caused 35 to rotate. The various cutters are thus caused to revolve, the teeth 9 being brought into operative engagement with the earth, rock or other material to be cut.

I do not limit myself to any special shape 40 for the teeth; neither do I limit myself to the precise construction and arrangement shown, the scope of my invention being com- mensurate with my claims.

Having thus described my invention, 45 what I claim as new and desire to secure by Letters Patent is as follows:

1. A drill comprising a revoluble member, a disk engaging the same and a cutter pro- 50 vided with stems, one of said stems being secured to said disk and another of said stems extending through said disk and being secured to said revoluble member.

2. A drill comprising a revoluble mem- 55 ber, a disk provided with holes and with countersinks merging into some of said holes, cutters provided with stems extending through all of said holes, means for securing some of said stems to said revoluble member, and nuts located within said countersinks and engaging the stems extending through the holes into which said counter- sinks merge.

FRED RICHARD WEATHEESBY.
